US00D786798S

(12) **United States Design Patent** (10) **Patent No.:** **US D786,798 S**
(45) **Date of Patent:** **** May 16, 2017**

(54) **ELECTRICAL CONNECTOR**

(71) Applicant: **Japan Aviation Electronics Industry, Limited**, Tokyo (JP)

(72) Inventor: **Yohei Yokoyama**, Tokyo (JP)

(73) Assignee: **JAPAN AVIATION ELECTRONICS INDUSTRY, LIMITED**, Tokyo (JP)

(**) Term: **14 Years**

(21) Appl. No.: **29/509,018**

(22) Filed: **Nov. 13, 2014**

(30) **Foreign Application Priority Data**

May 26, 2014 (JP) 2014-011142

(51) **LOC (10) Cl.** **13-03**

(52) **U.S. Cl.** **D13/147**
USPC **D13/147**

(58) **Field of Classification Search**

USPC D13/133, 134, 146–148, 153, 154, 184,
D13/199

(57) **CLAIM**

The ornamental design for an electrical connector, as shown and described.

DESCRIPTION

FIG. 1 is a front view of an electrical connector showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view showing a front, top and right side thereof;

FIG. 8 is a perspective view showing a rear, bottom and left side thereof;

FIG. 9 is a perspective view showing a front, right side and bottom thereof; and,

FIG. 10 is a perspective view showing a rear, left side and top thereof.

The broken lines depict portions of the electrical connector that form no part of the claimed design.
